UNITED STATES PATENT OFFICE.

FRANK RABBIT, OF BROOKLYN, MARYLAND.

ANTIGLARE DEVICE FOR VEHICLE HEADLIGHTS.

Application filed December 4, 1925. Serial No. 73,215.

This invention relates to anti-glare devices for vehicle head-lights, and includes an attachment, for head-lights of ordinary construction, for modifying or mitigating the glare of such head-lights while increasing the forward reach of the greater portion of the light that emanates from the light source or bulb.

Important objects of this invention are to provide a device of this character which will effectively and efficiently perform the functions specified in the foregoing, which is of simple construction so it is comparatively inexpensive, which can be very quickly and easily attached and detached to numerous forms and kinds of headlights without the use of any tool or implement, and which includes a very effective and practical means for retaining itself in its attached position while eliminating all rattling or wabbling of the light-bulb and of itself.

Other objects and important features are pointed out or implied in the following details of description, in connection with the accompanying drawings in which:

Fig. 1 is a vertical central sectional view through an anti-glare device of this improved construction attached to a head-light of well known construction. Fig. 2 is a side elevation of my anti-glare attachment detached from the head-light. Fig. 3 is a side elevation of the rear or base-section detached from the front or projecting section. Fig. 4 is a front view of the part shown in Fig. 3.

Referring to these drawings in detail, in which similar reference characters refer to similar parts in the several views, and in which the ordinary headlight comprises or includes a reflector 5, a lamp-socket 6, a lamp or bulb 7 and an ordinary bayonet-slot and stud 8 as the fastening means for the lamps. The attachment for such head-light will now be described as follows:

A concavo-convex base member 9 is circular in outline and has a central opening 10 for receiving the front end of the socket 6. The margin of the opening 10 has pliable tongues 11 integral therewith, this member 9 being preferably of a blank of sheet metal pressed into the concavo-convex shape, and it is also formed with integral tongues 12 that extend from the perimeter of the same and converge with relation to one another. The purpose of the tongues 11 is to form fasteners for a helical compression spring 13,

by bending them over the rear convolution of said spring, as more clearly shown in Fig. 1. The purpose of the tongues 12 is to form channels for receiving and holding tongues 14 which are formed on the rear or inner margin of the hollow frusto-conical front section or semi-reflector 15. The opposite edges of the tongues 12 are turned inward to form such channel, as more clearly seen in Fig. 1. By this means of securing the front section 15 to the rear section 9, these sections can very easily be connected to one another, and in this connection, it should be understood that the section 15 is of sheet metal which is pliable enough to permit the tongues 14 to be bent out at the proper angle to the axis of the sections 9 and 15, and springy enough to permit the tongues 14 to be inserted in the grooved tongues 12, and held therein by the springy action of the section 15. These sections may either be of unpolished aluminum, or of other sheet metal coated with aluminum paint, so all parts thereof (except not essentially the rear part of the rear section) have semi-reflecting surfaces.

The spring 13 performs the dual function of holding the bulb 7 against rattling or wabbling in its socket 6, and cooperating with the lamp or bulb and the fastening means 8 for holding the rear section 9 firmly on its seat so it will not rattle or wabble. To secure the attachment in place on its seat, the bulb is first removed from the socket 6, the part 9 placed on its seat, and the plug of the bulb is then forced through the entrance of the socket, against pressure of the spring 13, and turned for locking by means of the bayonet-slot and stud 8, thereby securing all parts of the invention firmly in the anti-glaring relation to one another.

The operation or effect of the anti-glaring device is as follows:

Since it is seen that the greater part of the bulb is surrounded by the front section 15 in such relation that very few of the light-rays are permitted to emanate directly to the full-reflecting or polished or bright surface 5, and in such relation that the light-rays do not emanate directly on the intermediate part of the reflecting surface that usually produces the dangerously blinding glare, and that the direct rays from the light-bulb are most all met and deflected or reflected from the semi-reflecting surface of the section 15, it

is evident that these light rays are softened or mitigated, and at the same time projected further forward because of the frusto-conical shape of this front section. It will also be seen that part of the light-rays emanate back to the semi-reflecting surface of the rear section 9, and are reflected thence against the outer semi-reflecting surface of the section 15, also against the reflecting surface of the reflector 5, thereby diffusing these rays of light and giving ample light along the sides of the road.

No attempt is here made to give a full explanation of all the theories of the effects produced, but the inventor has repeatedly tested the device at various distances of light-projection, and has found it very effectively eliminates the glare that is so objectionable and dangerous to traffic and to the traveling public.

It is not my intention to limit my patent protection to the exact construction and arrangement here shown, for the invention is susceptible of various modifications within the scope of the claims.

What I claim as my invention is:

1. In an attachment for a head-light including a reflector; the combination of a hollow and rearwardly converging front light-reflective section having an aperture in its convergent end to receive an electric light bulb, a concavo-convex rear light-reflective section having a central aperture therethrough for receiving the plug of said light bulb, this rear section having forwardly extending tongues on its outer edge, and means on the rear part of the rearwardly converging section for securing said tongues thereto.

2. In an attachment for a head-light including a reflector, the combination of a hollow and rearwardly converging front light-reflective section having an aperture in its convergent end to receive an electric light bulb, a concavo-convex rear light-reflective section having a central aperture therethrough for receiving the plug of said light bulb, the said front section having tongues formed on and extending rearwardly from its rear end, and means on said rear section for securing said tongues thereto.

3. In an attachment for a head-light including a reflector, the combination of a hollow and rearwardly converging front light-reflective section having an aperture in its convergent end to receive an electric

light bulb, a concavo-convex rear light-reflective section having a central aperture therethrough for receiving the plug of said light bulb, the said rear section having a set of forwardly extending tongues on its outer edge, the said front section having a set of rearwardly extending tongues on its rear end, and means on one set of tongues for removably securing the other set of tongues thereto.

4. The structure defined by claim 3, the said means including channels on one set of tongues to receive the other set of tongues, one or both sets of tongues being somewhat springy, and the tongues of each set being at an angle to one another, whereby these tongues are removably secured by their angular relation to one another.

5. In an attachment for a head-light including a reflector and a lamp socket, the combination of a hollow and rearwardly converging front light-reflective section having an aperture in its convergent end to receive an electric light-bulb, a rear light-reflective section having a central aperture therethrough for receiving the plug of said light-bulb, means extending from said rear section to said front section for supporting the latter in position around an electric light bulb, and a helical compression spring secured around said aperture of the rear section and adapted to receive said plug and being effective to removably secure said plug in said lamp-socket.

6. An anti-glare device including a hollow front section of frusto-conical shape and having both inner and outer surfaces of a semi-reflecting character, a rear section which is circular and concavo-convex and formed with tongues having channels therein, the front section having tongues on its smaller rear end to enter said channels for securing the front section to the rear section in spaced relation, the rear section being of a greater diameter than the rear end of the front section, the rear section having a central opening and provided with a helical compression spring secured thereto at the margin of said opening and surrounding the opening, whereby the anti-glare device can be secured in a head-light in the manner shown, for the purpose specified.

In testimony whereof I affix my signature.

FRANK RABBIT.
